UNITED STATES PATENT OFFICE.

ALECK BAUER, OF CHICAGO, ILLINOIS, ASSIGNOR TO BAUER & BLACK, OF CHICAGO, ILLINOIS, A CORPORATION OF ILLINOIS.

FOLDING DISPLAY-BOX.

SPECIFICATION forming part of Letters Patent No. 710,407, dated October 7, 1902.

Application filed July 27, 1901. Serial No. 69,913. (No model.)

To all whom it may concern:

Be it known that I, ALECK BAUER, a citizen of the United States, residing at Chicago, in the county of Cook and State of Illinois, have invented certain new and useful Improvements in Folding Display-Boxes, of which the following is a specification.

This invention relates to novel improvements in folding display-boxes of the kind usually made of pasteboard and variously called "cartons" or "envelops" or "wrappers." It is designed more especially for holding suspensory bandages; and its object is to provide a box which will securely hold the bandage, so that it can be used for mailing and shipping purposes, and which is constructed so that it can be unfolded and used to display the bandage without in any wise disturbing the arrangement thereof and so that the bandage can be readily removed for further inspection and replaced.

With this and other ends in view the invention consists in the novel construction and arrangement of parts hereinafter described, and illustrated in the accompanying drawings, in which—

Figure 1 is a perspective view of my improved box, showing the same folded. Fig. 2 shows the box unfolded in display position and a bandage arranged therein. Fig. 3 is a perspective view of the box closed. Fig. 4 is a detail perspective view at one end of the support.

Like letters of reference designate similar parts in each of the figures of the drawings, and referring thereto A designates the bottom, B the top, C D the end flaps, E the tucking-flap, R the front, K the ends, and S the back, of my improved box, all of these parts being preferably connected together and formed out of a single blank. The ends, front, and back are comparatively narrow and of corresponding width, the front R forming the connection between the top and tucking-flap, the back S connecting the top and bottom, and the ends K connecting the end flaps to the bottom. The back and ends are formed by bending or scoring the blank on parallel lines, so that they can be readily folded together in the form of a flat package or box, as shown in Figs. 1 and 3.

The tucking-flap is provided with tongues F to enter slits G in the bottom for the purpose of securing the box when folded and closed.

On the inner face of the bottom and near the top thereof I provide a support H, upon which the bandage is hung, and in order that the bandage may be held in the box in a proper manner and so that it can be displayed with effect I preferably make the support in the form of a strip of pasteboard or other material which extends across the bottom of the box and is secured thereto at its lower portion I by glue or any suitable fastening means, the upper portion thereof being free from the box.

The box is constructed of a size adapted to accommodate the particular bandage which it holds, and the band J of the bandage is slipped on the support and is held thereby in a convenient manner for displaying the bandage and for preventing its becoming disarranged in the box during transportation. Shoulders h may be provided at the ends of the support, against which the lower edges of the band J will abut when the bandage is hung on the support; but this is not necessary, and the ends of the support may be made without said shoulders, as shown Fig. 4.

The bandage is arranged upon the support in such a manner that the box may be hung up unfolded to display the bandage to advantage, and for this purpose I provide an opening L in the tucking-flap to receive a hook or other suspending device. The different parts of the box may be used for advertising purposes and bear labels and printed matter of a suitable nature, and it will be apparent that when the box is hung up unfolded, as shown in Fig. 2, the advertising will be prominently displayed as well as the bandage.

For holding bandages I prefer to make the box of rectangular shape and flat, the space between the top and bottom being preferably of sufficient depth only to provide for the article.

My improved box constructed in accordance with this invention is strong and will maintain its shape under all ordinary conditions and not easily become disfigured or broken. The end flaps fit beneath the top of the box and hold the ends in position to

constitute a support for the top and bottom, and the front and back are arranged to brace and support the top and bottom at their other edges, so that the box will be braced around 5 its edges by the front, back, and ends and at its middle by the article contained therein.

My improved box holds the bandage securely in place and at the same time permits of its examination and inspection without 10 unnecessary handling, which frequently soils and otherwise injures such articles; but at the same time it can be readily removed from the support and replaced thereon.

I am aware that changes in the arrangement of the different parts of my invention 15 may be made without departing from the spirit or sacrificing the advantages thereof— as, for example, the ends C D may be arranged on the top B, the tucking-flap may be 20 located at the lower edge of the bottom, a single tongue may be provided at the center of the tucking-flap to enter a properly-disposed slit in the bottom, the top and bottom may be transposed, and other changes of an obvious 25 character may be made. The proportions of the different parts may be changed to adapt the box for bandages of different sizes and for holding any other articles, as it will be understood that I do not limit the invention 30 to its use in connection with suspensory-bandages, and the box may be made of other material than pasteboard.

Instead of attaching the support to the box at its lower portion, as shown, I may attach 35 it at the middle and leave the ends free or attach it at one end, leaving the other end free.

Having thus fully described my invention, what I claim, and desire to secure by Letters 40 Patent, is—

1. A folding display-box, comprising a bottom, a top, a back connecting the top and bottom along their adjacent edges, a tucking-flap, a front connecting the top and tucking-flap along their adjacent edges, end flaps, ends 45

connecting the end flaps and bottom along their adjacent edges and a support consisting of a strip of pasteboard or other material fastened at its lower edge to the bottom and adjacent to the back of the box and having its 50 upper portion free from the box, substantially as described.

2. A folding display-box for suspensory bandages and other articles formed out of a single blank and having a bottom, a top corresponding to the bottom in size and shape, 55 a back and a front at opposite edges of the top and formed by bending or scoring the blank on parallel lines, ends at opposite edges of the bottom, similarly-formed end flaps connected to the ends and arranged to fold beneath the top and on the article in the box, a tucking-flap connected to the front and arranged to fold on the outer side of the bottom and provided with tongues to enter slits in 60 the bottom, the top and bottom of the box being braced and supported at the front and back edges thereof by the front and back and at the end edges thereof by the ends and end flaps and inside their edges by the article in 65 the box and a support within the box for holding the article, substantially as described.

3. In a folding display-box, a support consisting of a strip of pasteboard or other material located adjacent to the upper edge of 75 the bottom of the box, that portion of said strip extending from end to end thereof and from its lower edge to a line between its upper and lower edges being fastened to the bottom of the box and holding the upper portion of the strip close to the bottom of the box but free therefrom to enter the band of 80 a suspensory or other article for holding and suspending the same against the bottom of the box.

ALECK BAUER.
